BUILDING SCREEN WALL

Gordon J. Clauss, 2705 Katherine St., Fort Myers, Fla.

Filed Feb. 11, 1963, Ser. No. 73,513

Term of patent 14 years

(Cl. D18—2)

FIG. 1

FIG. 2

FIG. 1 is a front elevational view of a building screen wall embodying my new design; and

FIG. 2 is a perspective view of one of the blocks shown in FIG. 1.

I claim:

The ornamental design for a building screen wall, as shown.
